MOVING PICTURE PROJECTOR BASE

Fritz Albert Blank, New Rochelle, N. Y., assignor, by direct and mesne assignments, of one-half to A. Kip Livingston, West Hempstead, N. Y., and one-half to Longines-Wittnauer Watch Co., Inc., New York, N. Y., a corporation of New York

Application November 5, 1957, Serial No. 48,346

Term of patent 14 years

(Cl. D61—1)

Fig. 1.

Fig. 2.

Fig. 1 is an elevational perspective view of the moving picture projector base embodying my new design, showing the front, the top and right side thereof; and

Fig. 2 is a similar elevational perspective view of the moving picture projector base illustrated in Fig. 1, showing the back, the top and left side thereof.

I claim:

The ornamental design for a moving picture projector base, as shown.
